[57] ABSTRACT

An open top railway freight car having a bulb angle element joined by welding or riveting along the top edge of each of its sidewalls, each element being so designed as to concentrate one-half the resultant vertical loads of a shakeout machine resting thereon in direct vertical alignment with each sidewall thereby substantially avoiding a weakening of the joint between each element and the car sidewalls during a shakeout operation. Such a design of each element includes a built-up portion extending upwardly and inwardly along the corner thereof, the inwardly extending built-up portion also serving to space the inner leg of the foot members of the shakeout machine away from the riveted joint between the bulb angle elements and the car sidewalls during the shakeout operation.

OPEN TOP RAILWAY FREIGHT CAR HAVING BULB ANGLE ELEMENT ALONG TOP EDGE OF SIDEWALLS

This invention relates generally to open top railway freight cars, and more particularly to a specific type bulb angle element secured along the top edge of each sidewall of the freight car.

Because the bulk material transported in open top railway freight hopper cars oftentimes becomes packed to such an extent as to impede free discharge through the open hoppers, shakeout machines are used to expedite unloading of the bulk materials therefrom by inducing combinations of vertical, lateral or longitudinal vibrations to the car. Such shakeout machines ordinarily include spaced foot members resting along the top chords or bulb angle elements of the car sidewalls so that the cars may be shaken clean during unloading without further attention under normal conditions, thus saving both time and labor. Various types of shakeout machines are available and vary in weight, method of application and vibratory intensity. During vibration of the machine, severe lateral and vertical forces are transmitted to the car sidewalls, thereby subjecting the upper chords or bulb angle elements to heavy bending and vibration forces oftentimes causing the joints between the bulb angle elements and the sidewalls to severely deteriorate as well as causing fatigue and ultimate cracking of the metal sheet sidewalls between the welds or rivets thereof.

One approach taken in avoiding metal fatigue of the hopper car sidewalls is disclosed in U.S. Pat. No. 2,694,498 issued to William F. Dietrichson. An impact device for hopper cars is made use of therein, such device extending along and secured to the top chords of the sidewalls with a cushion member located therebelow for cushioning the impacts made by the vibration-agitation device. However, the joint between each top chord and car sidewall becomes severely weakened or even broken because of the repeated bending moments on the top chord produced by the agitating device. An earlier developed bulb angle element has attempted to solve this problem by providing a continuous upward extension along the horizontal leg of the angle element near the corner portion thereof for reducing the moment arm of resultant forces of the vibrator exerted about the joint between the angle element and the sidewall. Accordingly, this joint has been shown to weaken to a lesser extent than before during the vibration or shakeout operation. Nevertheless, the aforementioned problems still persist.

It is therefore an object of the present invention to provide an open top railway freight hopper car as having bulb angle elements joined along the upper edges of each sidewall thereof, each such angle element being so designed as to concentrate one-half the resultant vertical loads of a shakeout machine in a substantially direct vertical alignment with each sidewall thereby substantially avoiding a weakening of the joint between the angle elements and the car sidewalls during the shakeout operation.

Another object of this invention is to provide such a freight car wherein the bulb angle elements each include a built-up portion extending upwardly and inwardly along the corner thereof, the inwardly extending built-up portion also serving to space the inner leg of each foot member of the shakeout machine away from the riveted connection between the angle ele-

ments and the car sidewalls during the shakeout operation.

A further object of this invention is to provide such a freight car wherein both riveted and welded joints between the bulb angle elements and the car sidewalls are less likely to become weakened during the shakeout operation.

Other objects, advantages and novel features of the invention will become apparent from the following description of the invention when taken in conjunction with the accompanying drawings wherein:

FIG. 1 is an elevational view in cross-section showing an open top railway freight hopper car with the bulb angle elements mounted in place and a shakeout machine resting on the angle elements;

FIG. 2 is a side elevational view showing a portion of the freight car sidewall and bulb angle element of FIG. 1;

FIG. 3 is a sectional view of the bulb angle element and sidewall portion taken along the line 3-3 of FIG. 2;

FIG. 4 is a sectional view similar to FIG. 3 showing another embodiment of the invention wherein the bulb angle element is riveted to the freight car sidewall; and

FIG. 5 is a side elevational view showing a portion of the riveted joint of the FIG. 4 embodiment.

Turning now to the drawings wherein like reference characters refer to like and corresponding parts throughout the several views, the open top railway freight hopper car is shown in FIG. 1 generally designated 10, a showing of many of the details thereof being omitted for the sake of clarity. The car includes standard sidewalls 11 of metal plates mounted in any conventional manner with side stake members 12 secured in place as by rivets 13 (see FIG. 2). An upper portion of each vertical stake member 12 is reversely bent as at 14 to accommodate a bulb angle element 15 shown in detail in FIG. 3. Each such element for each sidewall includes a horizontal leg 16 and a vertical leg 17 depending therefrom. Leg 16 has an outwardly and downwardly extending bulbed flange 18 which is standard for providing additional strength for the angle element. A built-up portion 19 of the same material as the remainder of the bulb angle element is provided for each such element along the corner thereof, i.e., at the intersection of the vertical and horizontal legs. This built-up portion extends both upwardly from the top surface of horizontal leg 16 as well as inwardly of the inner surface of vertical leg 17. The thickness of the upwardly extending built-up portion 19 from the top surface of leg 16 to the top surface 21 thereof is substantially equal to the thickness of leg 16. Also, the thickness of the inwardly extending built-up portion 19 from the inner surface of vertical leg 17 to the inner surface 22 thereof is substantially equal to the thickness of leg 17. The dimensions of the angle element are such that undersurface 23 of the inwardly extending built-up portion lies in the same plane as the undersurface of horizontal leg 16. Moreover, approximately half the upwardly extending built-up portion lies on each side of a centerline 24 thereby forming a T-section as defined by surfaces 21 and 22, imaginary line 25 and leg 17.

A shakeout machine generally designated 26 has a motor 27 operatively connected to frame 28 thereof for vibrating the frame and each of the spaced foot members 29 interconnected with the frame as at 31. Each

foot member 29 has inner and outer depending flanges 32 and 33 respectively lying inwardly and outwardly of each of the bulb angle elements. A portion of a foot member is shown in phantom in FIGS. 3 and 4 for the sake of clarity, each foot member resting on top surface 21 of built-up portion 19.

In the FIG. 3 embodiment, the lower end of each vertical member 17 of each bulb angle element is joined along the upper edge of its respective sidewall 11 as by means of a continuous weld 34 (see also FIG. 2). In the FIGS. 4 and 5 embodiment, on the other hand, the lower end of each vertical leg 17 is joined along its respective sidewall 11 by means of a riveted connection. Such a connection includes the use of a continuous gusset plate 35 continuously riveted as at 36 and 37 respectively to leg 17 and sidewall 11.

The specific design of each bulb angle element permits one-half the resultant static and dynamic vertical loads produced by the shakeout machine during its operation to be concentrated in a substantially direct vertical alignment with each sidewall 11 along respective centerlines 24 so as to cause these loads to be transmitted substantially evenly to the upper ends of the sidewalls. Accordingly, the continuous weld 34 is not subjected to those bending movements as before since the moment arm of these loads or forces during the shakeout operation is substantially reduced to zero. Any weakening or deterioration of weld 34 is thereby substantially minimized.

The same result is effected for the FIGS. 4 and 5 embodiments, i.e., direct transmission of all the loads during the shakeout operation evenly to the upper end of each sidewall thereby substantially avoiding any bending of gusset plates 35. Accordingly, any weakening or deterioration of the joint along riveting 36 and 37 is substantially minimized. Moreover, the built-up portion which extends inwardly and terminates at inner surface 22 also serves to maintain inner leg 32 of each foot member spaced apart from vertical legs 17 during the shakeout operation so that any contact between legs 32 and riveting 36 is substantially avoided.

From the foregoing, it can be seen that a quite simple approach has been taken in substantially reducing to zero those loads from a shakeout machine during its operation so as to concentrate one-half the resultant

loads directly in alignment with the freight car sidewalls to thereby evenly distribute the load along the upper edges of the sidewalls. Deterioration of the joints between the bulb angle elements and the sidewalls is therefore minimized with the use of an inexpensive and highly effective design for the bulb angle elements.

Obviously, many modifications and variations of the present invention are possible in the light of the above teachings. It is therefore to be understood that within the scope of the appended claims, the invention may be practiced otherwise than as specifically described.

What is claimed is:

1. An open top railway freight hopper car having spaced sidewalls, an elongated bulb angle element joined along the upper edge of each said sidewall, each said element comprising a vertical leg and a horizontal outwardly extending leg integrally interconnected therewith forming a corner, said vertical leg being continuously joined along its free end to each said upper edge of said sidewalls, and said bulb angle element having a built-up integral portion extending upwardly and inwardly along said corner, said portion serving to concentrate one-half the resultant static and dynamic vertical loads of a shakeout machine in direct vertical alignment with each said sidewall substantially along the vertical centerline of said vertical leg, which shakeout machine spans the freight car between said sidewalls and rests by means of its spaced foot members directly on the top surface of said upwardly extending portion, whereby any weakening of the joints between said upper edges of said sidewalls and said free ends of said vertical legs is substantially avoided.

2. The freight car according to claim 1 wherein said vertical leg of each said bulb angle element is joined along its free end to each said upper edge of said sidewalls by means of a gusset plate continuously riveted to both said vertical legs and said sidewalls respectively, said inwardly extending built-up portions serving also to maintain the inner legs of the foot members of the shakeout machine spaced apart from said vertical members during operation of the machine, thereby substantially avoiding contact between the inner legs and the riveted joints between said bulb angle elements and said sidewalls.
